[73] Assignee:

[57] CLAIM

[**] Term: 14 Years

The ornamental design for a spring-clipped crutch attachment basket, as shown and described.

[21] Appl. No.: 537,761

DESCRIPTION

[22] Filed: Jun. 14, 1990

FIG. 1 is a perspective view of a spring-clipped crutch attachment basket showing my new design;

[52] U.S. Cl. D3/10

FIG. 2 is a left side elevational view;

[58] Field of Search D3/5-17,
D3/42; 135/15.1, 65, 66, 76, 77, 910, 911;
D9/305

FIG. 3 is an exploded top plan view;

FIG. 4 is a front elevational view with one handle partially lowered;

FIG. 5 is a rear elevational view; and

FIG. 6 is a rear elevational in mounted position.

The broken line showing of a crutch in FIG. 6 is for illustrative purposes only and forms no part of the claimed design.
